UNITED STATES PATENT OFFICE.

WILLIAM L. CAMPBELL, OF MELISSA, TEXAS, ASSIGNOR OF ONE-FOURTH TO FRED BRIDGEFARMER AND ONE-FOURTH TO JOHN E. SCRIBNER, BOTH OF MELISSA, TEXAS.

ROTARY ENGINE.

1,322,162.

Specification of Letters Patent. Patented Nov. 18, 1919.

Application filed January 8, 1919. Serial No. 270,204.

To all whom it may concern:

Be it known that I, WILLIAM L. CAMPBELL, a citizen of the United States, residing at Melissa, in the county of Collin and State of Texas, have invented certain new and useful Improvements in Rotary Engines, of which the following is a specification, reference being had to the accompanying drawings.

10 This invention relates to engines, and particularly to rotary engines using steam, compressed air, or other elastic fluid, as motive fluid.

15 The general object of my invention is to provide a rotary engine of a very simple and compact character, which may be made extremely light in proportion to the power developed thereby.

20 A further object is to provide means whereby the engine may be readily started or stopped or reversed.

25 A still further object of the invention is to so construct the engine that the power of the engine may be greatly increased or decreased and the stroke of the pistons increased or decreased correspondingly.

30 A further object is to so construct the engine that power may be taken directly from the rotor without the use of intermediate gearing.

35 And still another object is to provide means whereby the engine may be automatically lubricated while running.

Other objects relate to the details of construction and arrangements of parts, as will appear hereinafter.

My invention is illustrated in the accompanying drawings, wherein:—

Figure 1 is a fragmentary top plan view 40 of an engine constructed in accordance with my invention;

Fig. 2 is a side elevation thereof;

Fig. 3 is an enlarged fragmentary vertical section on the line 3—3 of Fig. 1;

45 Fig. 4 is a sectional view of the several cylinders and the hub of the cylinders;

Fig. 5 is a fragmentary vertical sectional view through the hub and the adjustable pivot for the connecting rods;

50 Fig. 6 is a section on the line 6—6 of Fig. 5;

Fig. 7 is a section on the line 7—7 of Fig. 3;

Fig. 8 is a section on the line 8—8 of 55 Fig. 3;

Fig. 9 is a fragmentary face view of the port;

Fig. 10 is a top plan view of the base or guideway for the slide.

Referring to these drawings, and particularly to Figs. 1, 2 and 3, 10 designates a base which may be of any suitable character and 11 designates uprights mounted upon the base and having bearings at their upper ends for a transverse shaft 12 which, 60 at one end, may be provided with a handle 13 of any character and which is screw threaded at its middle, as at 14.

Mounted upon the base 10 and extending upward therefrom is a centrally disposed, 70 fixed shaft 15 upon which the rotor revolves, this shaft 15 being formed with a base 16 which is attached to the base 10 in any suitable manner or may be formed as part thereof. Preferably, this shaft 15 is 75 tapered above the base and may be provided with suitable bearings as, for instance, ball or other anti-friction bearings for the support of the rotor. The rotor consists of upper and lower disks 17 and 18 attached to or 80 forming part of an annular hub 19, from which extend a plurality of radially disposed cylinders 20, these cylinders being disposed between the disks 17 and 18 or formed as part of these disks or attached 85 thereto in any suitable manner. Each cylinder 20 is closed at its outer end, as at 21, this outer end being provided with a stuffing box through which passes the piston rod 22 carrying a piston 23 operating within the cylinder. The outer end of each piston rod is connected to a cross head 24 of the form illustrated in Fig. 8, this cross head 90 operating in radially disposed cross head guides 25 illustrated as angular in form, and attached to or formed as part of, or otherwise connected to the upper and outer disks 17. The periphery of the rotor is formed by an annulus 26 which fits between the plates 17 and 18 and may be bolted thereto. 95 This annulus 26 constitutes a rim for the rotor and may be used as a band wheel to transmit power from the rotor to the driven mechanism. It will be seen from Fig. 3 of the drawings that the lower cross head 24 guides 25 are disposed above the lower disk 18 to permit a pipe 27 or other duct to extend from the outer end of each cylinder 20 into the hub 19 of the rotor.

Each of the disks 17 is radially slotted at 110

its margin and a stud bolt 28 extends up from each cross head 24 through the corresponding slot 29, and to each stud bolt is pivoted a connecting rod 30. These connecting rods may be of any suitable character and extend inward and are pivoted upon a stud 31 extending upward from a slide 32. This slide 32 is mounted upon a diametrically extending guide plate 33 having upwardly and inwardly extending guide flanges 34 which overhang and extend over the slide 32. The upper end of the stud 31 carries upon it a U-shaped yoke 35, the two arms of which are screw threaded for engagement with the screw threaded rod 14, as illustrated in Figs. 2 and 5. By rotating the screw shaft 12, the yoke 35 will be shifted diametrically across the center of the rotor and this will shift the slide 32 in its guides 34. When the slide 32 is in its central position relative to the periphery of the rotor, it is obvious that there will be no movement of the pistons whatever, but that as the slide is shifted into an eccentric relation with the rotor, reciprocation will be given to the pistons as the rotor revolves, but conversely that if the pistons are reciprocated by fluid pressure, a movement of rotation will be given to the rotor.

It is obvious also that the further away the stud 31 is shifted from the center of the rotor, the greater will be the stroke of the pistons and the nearer it is shifted to the center of the rotor, the less will be the stroke of the pistons, and it will be also obvious, assuming the slide has been shifted to one side of the center of the rotor with the rotor revolving in one direction, then if the slide be shifted across the center of the rotor to the opposite side, the rotor will be reversed in its movement.

For the purpose of permitting fluid to enter each cylinder in succession to force the piston therein outward and then permit the live fluid to be forced into the other end of the cylinder and the exhaust steam discharged, I form the central fixed shaft 15 with a longitudinally extending inlet port 36 which extends longitudinally through the shaft or axis 15 and at its lower end extends laterally and is connected to a steam or air supply pipe 37 provided with a throttle valve 38. The central shaft 15, as illustrated in Figs. 3 and 4, is formed opposite the longitudinal axes of the cylinders 20 with a pair of oppositely disposed, arcuate channels 39 and 39^a separated by an intermediate web 40. The port 36 at its upper end or its end opposite its connection to the pipe 37, is laterally extended into one of said channels 39 and intermediate the lower end of this duct 36 and the upper end of the duct, this port or duct 36 communicates with an arcuate channel 41. This vertical shaft is also provided with an exhaust duct

42 which extends longitudinally through the shaft and whose upper end is connected to the channel 39^a and to a channel 41^a opposite the channel 41. The hub 19 of the rotor is formed at the inner end of each cylinder with a port 43 which will successively register with the channels 39 and 39^a and this hub 19 is also formed with ports 44, one for each cylinder, into which the pipes 27 from the several cylinders open, these ports 44 being adapted to register with the channels 41 and 41^a as the rotor rotates. It will be seen from Fig. 3 that when one of the cylinders 20 has its pipe 27 in communication with the channel 41, the port 43 will be in communication with the channel 39^a, while another cylinder of the plurality of cylinders will be in communication through port 43 with channel 39 and through pipe 27 with channel 41^a. Under these circumstances, live steam for one of the cylinders 20 will pass through the pipe 27 into the space behind the piston and force the piston inward while the exhaust passes out to the channel 39^a and thence out through the exhaust duct 42, while at the same time live steam is passing from the steam duct 36 into the other cylinder through port 43 and channel 39 and exhaust is passing through the outer end of the same cylinder through pipe 27 to channel 41^a and thence into the exhaust pipe 42. Thus with the arrangement illustrated, there are always two pistons receiving steam or other motive fluid and one piston idle wherein the parts are on a center as it may be termed. It will be obvious, as before remarked, that the stroke of the pistons depends upon the eccentricity of the stud 31, to which connecting rods are pivoted and that when the stud 31 is disposed concentric to the fixed shaft or bearing 15, no reciprocation of the pistons will occur. For the purpose of adjusting the slide 33, I provide the screw threaded rod or shaft 12, but in order to steady the movement of the engine and hold the slide 33 in its adjusted position, I make the stud 34 annular, as illustrated in Fig. 6, and dispose in the central passage of this stud the vertical reciprocating pin 45 which, as illustrated in Fig. 5, is operatively connected to a bell crank lever 46 pivotally mounted upon the yoke 35, and which is connected by a rod 47 which extends over and through one of the parts 11 and is provided with any suitable handle. The bottom of the track or slideway 33 is formed with a plurality of notches 48, as shown in Fig. 10, these notches being adapted to receive the lower end of the pin and this pin 45, as shown in Fig. 6, is formed with one or more longitudinally extending oil ducts 49. The top of the stud 31 has a port 50 connected to an oil cup 51 so that oil may flow downward from this oil cup through the duct 49 and through the

slide 33 into the notches 48. These notches are connected by means of channels 52 with oil ports 53 which extend through the bottom of the slideway 33, as shown in Fig. 5, 5 to ducts 54 which extend downward in the fixed shaft or axis 15 and then laterally and at certain times discharge into upward extensions 55 of the ports 43. Now these oil ducts 53 are disposed in a plane at right angles to the plane of the ducts 36 and 42. In 10 other words, the ports 53 open upon the webs 40 which divide the channels 39 and 39^a from each other. As a consequence, as the rotor moves around the fixed central 15 shaft or axis, the upward extensions 55 of ports 43 will register with and pass over the ports 54 and will receive oil therefrom and then as the rotor moves to carry the ports 43 into alignment with the chambers or 20 channels 39 or 39^a, the inrushing steam or other motive fluid will carry inward the small globule of oil deposited in the extensions 55 and the oil will be distributed in the interior of the cylinder, reciprocating the 25 cylinder and the piston.

It is to be understood that one of the ports 53 is active when the engine is moving in one direction and is inactive when the rotor is moving in the other direction, as if both 30 ports were active at all times then while one cylinder was sucking in oil, the other would be blowing it out with the exhaust.

The operation of this motor will be obvious from what has gone before, but attention 35 is called again to the advantages of the motor. It will be seen that it is very light, very simple, and that inasmuch as the ports are opened and closed by the rotation of the rotor around the central fixed axis or shaft 40 that there is no complicated valve mechanism to get out of order. Furthermore, the power developed by the motor may be at all times readily controlled in accordance with the amount of load on the engine. Thus an 45 engine constructed in accordance with my invention is adapted to be used for a great many different purposes and where the load is constantly changing. Thus the same engine 50 may be used for driving a great number of different mechanisms and the engine 55 may have a large range of power. This engine obviates the necessity of using a ten-horse power engine, for instance, to drive a mechanism where three-horse power or one-horse power would be amply sufficient. It 60 will, therefore, be obvious that the range of usefulness of the engine is very great. I have described the engine as if the rotor was designed to revolve in a horizontal plane, but it is to be understood that the 65 rotor may rotate in a vertical plane or any other plane just as easy. The engine may be driven either by compressed air, steam, or other fluid pressure and it is obvious that 65 by a proper arrangement of valves, the en-

gine might be used as an internal combustion engine. It is further obvious that the mechanism can be used as a pump if it is driven by a suitable motor and that then the adjustment of the pin or stud 31 will 70 change the stroke of the pump pistons and thus control the amount discharged by the pump. It is obvious also, as before stated, that the engine may be readily reversed without shifting any valves and without 75 placing any strain upon the moving parts of the engine.

I claim:—

1. A rotary engine including a fixed bearing, a rotor mounted for rotation on said bearing and including a web, a plurality of radially directed cylinders disposed in conjunction with the web, pistons operating in said cylinders, a plurality of radially extending connecting rods, members operatively connecting the outer ends of the connecting rods to the pistons, the web being radially slotted at a plurality of points for the passage of said connecting members, a member to which the inner ends of all of said 80 connecting rods are pivoted, and means for adjustably shifting said member diametrically across the center of rotation of the rotor to thereby adjust the eccentricity of 85 said member relative to the rotor and thereby control the stroke of the pistons, said web being provided with a peripheral wall whereby power may be taken from the rotor. 90

2. A rotary engine including a rotor having a plurality of radially disposed cylinders, pistons operating in the several cylinders and having piston rods, connecting rods each pivotally connected to one of said piston rods, the connecting rods extending inwardly, a member to which the inner ends 100 of all of the connecting rods are pivoted, and means for shifting said member diametrically across the center of rotation of the rotor. 105

3. A rotary engine including a fixed bearing, a rotor mounted for rotation on said bearing and having a plurality of radially directed cylinders, pistons operating in said cylinders, a plurality of radially extending connecting rods operatively connected at 110 their outer ends to said pistons, a member to which the inner ends of all of said connecting rods are pivoted, means for adjustably shifting said member diametrically across the center of rotation of the rotor to thereby adjust the eccentricity of 115 said member relative to the rotor and control the stroke of the pistons, each cylinder being provided with a pair of ports communicating with opposite ends of the cylinder and the bearing being provided with inlet and exhaust ducts with which said ports are adapted to alternately connect. 120

4. A rotary engine including a rotor having a pair of parallel disks, a central an 130

nulus, a plurality of cylinders disposed between the disks and extending from said central annulus, a bearing upon which the annulus rotates, pistons in the several cylinders having piston rods, connecting rods pivotally connected at their outer ends to the piston rods, a member to which all of said connecting rods are pivoted, means for shifting said member diametrically across the center of rotation of the rotor from one side of said center to the other and holding said member locked in adjusted position, and means for alternately admitting motive fluid to opposite ends of the cylinder and discharging exhaust motive fluid alternately from opposite ends of each cylinder.

5. A rotary engine including a rotor, a bearing upon which the rotor is mounted and supporting a slideway extending diametrically of the rotor, a slide mounted upon said slideway, a plurality of cylinders carried by the rotor, pistons operating therein and having piston rods, a plurality of connecting rods pivoted at their outer ends to said piston rods and at their inner ends to said slide, and means for shifting the slide diametrically across the rotor including a screw threaded shank which engages said slide.

6. A rotary engine including a centrally disposed bearing, a rotor having a central annulus mounted on the bearing and provided with a plurality of radiating cylinders, the bearing extending through the annulus and rotor, a slideway mounted upon the bearing and extending diametrically across the rotor, a slide mounted in said slideway and having a stud extending parallel to the axis of the bearing, pistons operating in the cylinders and having piston rods, connecting rods pivotally connected to the outer ends of the piston rods and all pivotally connected to said stud, a yoke mounted on the stud, a rod having screw threads extending diametrically across the plane of rotation of the rotor and with which said yoke engages, the annulus being formed to provide a pair of longitudinally displaced ports for each cylinder, the ports being respectively connected to opposite ends of each cylinder, the bearing being formed to provide a pair of channels with which certain ports of the several cylinders intermittently register, and channels with which the other ports of the cylinders intermittently register, and the bearing being formed to provide an inlet duct opening into certain of said channels and a discharge duct opening into certain of said channels.

7. A rotary engine including a central bearing, a rotor mounted on said bearing and including an annulus, upper and lower disks attached thereto and spaced from each other, radiating cylinders disposed between

the disks, and a peripheral rim attached to the disks, one of said disks being slotted, pistons operating in the cylinders and having piston rods extending through said slots, connecting rods pivotally connected to the outer ends of the piston rods, cross heads operating in said slots and forming the connecting means between the connecting rods and the piston rods, a slideway supported upon the central bearing, a slide mounted in said slideway and having a stud to which the several connecting rods are pivoted, and means for shifting said slideway diametrically across the axis of the rotor, the annulus and the central bearing being formed to provide inlet and outlet ports and ducts.

8. A rotary engine including a central bearing, a rotor mounted upon said bearing for rotating therearound and including an annulus and radiating cylinders, a slideway mounted on the bearing, a slide mounted in the slideway, pistons operating in the cylinders and having piston rods, connecting rods pivoted to the piston rods and to the slide, means for shifting the slide, means for lubricating the several cylinders including a lubricant duct extending through the slide, and a pair of ducts extending through the bearing and opening upon the outer face thereof and with which said duct in the slide is adapted to communicate in any position of the slide, the rotor being formed with ports entering the cylinders and having extensions adapted in the rotation of the rotor to register with said lubricant ducts in the bearing.

9. A rotary engine including a centrally disposed bearing, a rotor mounted thereon having a central annulus surrounding the bearing, cylinders radiating from the annulus, spaced plates or disks between which the cylinders are disposed, one of said disks being slotted, pistons operating in the cylinders and having piston rods, radially shiftable cross heads slidably mounted in said slots and to which the piston rods are connected, connecting rods pivoted to said cross heads, a slideway mounted upon the bearing and extending diametrically of the rotor, a slide mounted in said slideway and having a stud to which the connecting rods are pivoted, means for shifting said slide along the slideway, and means for holding the slide in its shifted position including a pin passing through the slide, the slideway being formed with notches with which said pins are adapted to engage, and manually operable means for shifting the pin out of its engagement with a notch to permit the shifting of the slide.

10. A rotary engine including a centrally disposed bearing, a rotor mounted thereon having a central annulus surrounding the bearing, cylinders radiating from the annulus, spaced plates or disks between which

the cylinders are disposed, one of said disks being slotted, pistons operating in the cylinders and having piston rods, radially shiftable cross heads slidably mounted in said 5 slots and to which the piston rods are connected, connecting rods pivoted to said cross heads, a slideway mounted upon the bearing and extending diametrically of the rotor, a slide mounted in said slideway and having 10 a stud to which the connecting rods are pivoted, means for shifting said slide along the slideway, means for holding the slide in its shifted position including a pin passing through the slide, the slideway being formed 15 with notches with which said pins are adapted to engage, manually operable means for shifting the pin out of its engagement with a notch to permit the shifting of the slide, and means for lubricating the cylinders comprising 20 a channel formed in the locking pin and having communication with a source of oil, ducts formed in the central bearing and opening upon the upper face of the slideway and with which said channels in the pins 25 are adapted to register, said ducts in the bearing opening upon the periphery of the bearing, each cylinder being formed with a port having an extension, the extension being adapted to register with the ends of said 30 ducts as the cylinders rotate about the bearing.

11. A rotary engine including a centrally disposed bearing, a rotor mounted thereon including an annulus having radiating cylinders, pistons operating in the cylinders and having piston rods, a relatively fixed member disposed adjacent the center of rotation of the rotor, connecting rods pivoted to said 35 relatively fixed member and operatively connected to the piston rods, the annulus of the rotor being formed to provide a pair of ports for each cylinder longitudinally displaced with relation to each other, the ports being connected respectively to the outer and inner 40 ends of the corresponding cylinder, 45

the central bearing being formed to provide two pairs of oppositely disposed channels longitudinally displaced with relation to each other, a duct connecting diagonally opposite channels with an inlet port and a 50 duct connecting the other diagonally opposite channels with an outlet port.

12. A rotary engine including a centrally disposed bearing, a rotor mounted thereon including an annulus having radiating cylinders, pistons operating in the cylinders and having piston rods, a relatively fixed member disposed adjacent the center of rotation of the rotor, connecting rods pivoted to said 55 relatively fixed member and operatively connected to the piston rods, the annulus of the rotor being formed to provide a pair of ports for each cylinder longitudinally displaced with relation to each other, the ports being connected respectively to the outer and inner 60 ends of the corresponding cylinder, the central bearing being formed to provide two pairs of oppositely disposed channels longitudinally displaced with relation to each other, a duct connecting diagonally opposite 65 channels with an inlet port and a duct connecting the other diagonally opposite channels with an outlet port, the central bearing at its upper end being also provided with two ducts opening upon the face of the bearing and longitudinally displaced with relation to the adjacent channels in the bearing, said ducts communicating with a source of oil and one of said ducts being rendered 70 active and the other inactive when the rotor is rotating in one direction and vice versa, and one of the ports for each cylinder having an extension adapted to register with 75 said oil duct in the central bearing.

In testimony whereof I hereunto affix my 80 signature in the presence of two witnesses.

WILLIAM L. CAMPBELL.
